C. E. ANDERSON

PROCESS OF FORMING TURNBUCKLES

Filed Oct. 5, 1921

Inventor
Carl E. Anderson
By Sheridan Jones, Sheridan & Smith, Atty.

Patented July 22, 1924.

UNITED STATES PATENT OFFICE.

CARL E. ANDERSON, OF GRAND HAVEN, MICHIGAN, ASSIGNOR TO BOLLING MANUFACTURING COMPANY, OF GRAND HAVEN, MICHIGAN, A CORPORATION OF MICHIGAN.

PROCESS OF FORMING TURNBUCKLES.

Application filed October 5, 1921. Serial No. 505,630.

To all whom it may concern:

Be it known that I, CARL E. ANDERSON, a subject of the King of Sweden, residing at Grand Haven, in the county of Ottawa and State of Michigan, have invented certain new and useful Improvements in Processes of Forming Turnbuckles, of which the following is a specification.

This invention relates to improvements in clevises, turn buckles and the like, and to improvements in processes of forming the same.

The principal object of the invention is to provide improved means whereby the clevis or turn buckle is formed from sheet metal, thereby greatly simplifying and cheapening the process of manufacturing the device.

Other objects relate to various features of construction and arrangement and to various operations of forming these devices, as will be hereinafter more fully explained.

The nature of the invention will be understood from the following specification taken with the accompanying drawings, in which one form of clevis and one form of turn buckle, with one method of forming each of them are set forth.

In the drawings:—

Fig. 1 is a plan view of a sheet metal blank, which is partially cut away in carrying out the first step of the process of forming the clevis.

Fig. 2 is an end elevation of the partially formed clevis.

Fig. 3 is a side elevation of the completed clevis.

Fig. 4 shows vertical section through the clevis on line 4—4 of Fig. 3.

Fig. 5 shows an end elevation of the clevis looking toward the top thereof as viewed in Fig. 3.

Fig. 6 is a plan view of sheet metal blank showing the first step of the process of forming a turn buckle.

Fig. 7 shows a side elevation of the completed turn buckle, and

Fig. 8 shows a vertical section on line 8—8 of Fig. 7.

In Figs. 1 to 5 inclusive of the drawings the clevis is shown as formed from a sheet metal blank 10, which is partially cut away to form a member 11, having an upper body 11^a and two parallel arms 11^b. During the operation of stamping the member 11 from the metal sheet, apertures 12 are punched

through the lower ends of the arms 11^b, the metal being projected outwardly in forming these apertures to provide annular flanges 13. After the member 11 has been formed as illustrated in Fig. 1, the body portion 11^a 60 thereof is operated upon by a suitable die press or other device in order to bend the member 11^a into circular or cylindrical form thus providing a cylinder 14 at the upper ends of the two arms 11^b which are thus 65 drawn into position in parallel planes as shown in Fig. 4. Fig. 2 of the drawings shows the body portion 11^a partially bent into cylindrical form. After this bending operation has been completed, the meeting 70 edges 15 of the body portion 11^a may preferably be welded together in the cylindrical extremity of the clevis. An outer cylinder or collar 16 is preferably pressed onto the cylinder 14 in order to prevent the spreading thereof. The collar 16 may be drawn from sheet metal, or if desired, these collars may be cut from drawn metal tubing. After the parts have thus been formed, the cylinder 14 may be internally threaded as shown 80 at 17 to permit the ready connection thereof with a rod or other device with which it is to be used.

In Figs. 6, 7 and 8 of the drawings, there is illustrated a form of a turn buckle by a 85 similar process of manufacture. The first step in the formation of a turn buckle consists of cutting a sheet metal blank 20 to form a member 21, consisting of two upper and lower bands 22, connected by parallel 90 straps 23, an aperture 24 being provided between the straps, and the metal in the outer side thereof being cut away, as shown at 25. After the member 21 has been formed, the bands 22 are bent into cylindrical form, thus 95 forming cylinders 26 at the ends of the device with the connecting straps 23 lying in parallel planes. During this operation the straps 23 may be held apart so that they are slightly bowed in an outward direction 100 as shown in Fig. 8. After the cylinders 26 have thus been formed, collars 27 are preferably shrunk into position thereon in order to prevent separation of the meeting edges which, however, may be welded together as in the construction previously described. The cylinders 26 are shown as being internally threaded at 28.

The processes herein described provide a 110 ready means of forming clevises and turn

buckles from sheet metal and constitute a great improvement upon the practice heretofore known according to which devices of this kind have been forged or formed of 5 wrought metal.

Although certain methods of construction have been explained for the purpose of illustration, it will be understood that the devices herein described and the processes of 10 forming them may be altered in various ways without departing from the scope of the appended claims.

I claim:—

1. The process of forming a turnbuckle, 15 which comprises the operations of cutting a sheet metal blank to form a member having parallel transverse parts connected by parallel arms, and bending said transverse parts to form two cylinders and to bring said arms into parallel planes connecting said 20 cylinders.

2. The process of forming a turnbuckle,

which comprises the operations of cutting a sheet metal blank to form a member having parallel transverse parts connected by parallel arms, bending said transverse parts to form two cylinders and to bring said arms into parallel planes connecting said cylinders, and welding the meeting edges of said transverse parts. 25

3. The process of forming a turnbuckle, 30 which comprises the operations of cutting a sheet metal blank to form a member having parallel transverse parts connected by parallel arms, bending said transverse parts to form two cylinders and to bring said arms into parallel planes connecting said cylinders, and pressing cylindrical members on to said cylinders formed by bending said transverse parts. 35

In testimony whereof, I have subscribed my name.

CARL E. ANDERSON.
